UNITED STATES PATENT OFFICE

CHRISTIAN A. CADENBACH, OF ST. LOUIS, MISSOURI, ASSIGNOR TO INDEPENDENT DIE & SUPPLY CO., OF ST. LOUIS, MISSOURI, A CORPORATION OF MISSOURI

STILT-ANVIL DIE FOR SHOE CUT-OUTS

Application filed November 9, 1928. Serial No. 318,132.

My invention relates to stilt anvil dies, and has for its object to provide a die of that character which is a distinct and practical improvement to overcome certain practical objections to, and defects in the present types of stilt anvil dies, such as are used by shoe manufacturers for cutting through the leather and cloth linings of women's shoes to provide quarters, vamps, foxings, appliques, tips, etc., thereof with cutout openings, or perforations of the desired design.

Heretofore, it has been the practice to hingeably support the mask plate to an independent supporting post carried by the base of the device, and, to also support the safety kick member to a post, and, it is an essential object of my present invention to hingeably support the mask plate to an edge of the yieldably supported stripper plate, and to also secure the safety kick member to the stripper plate so that they will be carried thereby as a unit with the yielding movements of the stripper plate. The hinging of the mask plate to the stripper plate is essential in that it prevents the mask plate from being displaced from its normal registering position relative to the stripper plate from various causes.

A further object of the invention is the provision of a stilt anvil die which is comparatively light in weight, so that girls employed in a shoe factory can easily and readily handle the same, and, which has its parts so arranged that the die, or dies support the stripper plate, the mask plate and the safety kick member as a unit.

A still further object of the invention is the provision of a stilt anvil die which possesses advantages in points of simplicity and efficiency, and, at the same time proves itself comparatively inexpensive in cost of manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein

like characters of reference denote similar parts throughout the several views:

Fig. 1, is a top plan view of a stilt anvil die embodying the features of my invention and showing a shoe quarter positioned upon the device in readiness to be perforated.

Fig. 2, is a top plan view of the device with the mask plate swung back and out of register with the stripper plate.

Fig. 3, is an enlarged detail taken on line 3-3 of Fig. 1.

Fig. 4, is a side elevation of the device.

Referring to the drawings, the reference numeral 1 designates a suitable base plate, preferably of sheet fiber, or its equivalent, so as to reduce the weight and cost of the device, as much as possible.

One or more suitable dies designated 2 and having the raised tubular cutting edges 3 are rigidly supported above the base plate 1 by means of tubular supports 4 through which pass bolts 5, which bolts also pass through the base plate 1 and are screw threadedly connected at their upper ends to the dies 2. The lower end of each bolt 5 is provided with a suitable head 6 which is seated in a recess 7 in the lower face of the base plate 1.

A suitable stripper plate 8 is yieldingly supported by the die, or dies 2, and it is provided with cutout openings 9 corresponding in shape to the cutting edge of each die, but somewhat larger so as to surround or encircle the raised cutting edge of the die, or dies, thus permitting the stripper plate to be depressed causing the raised cutting edge of the die, or dies to enter the cutout openings of the stripper plate 8 without coming into contact with the edge of the cutout openings 9.

The means shown for guiding and directing compression and limiting ejection travel of the stripper plate 8 upon the die, or dies 2, comprises a plurality of suitable spaced guide studs 10 which pass through openings 11 in the dies. The upper end of each stud is preferably reduced in diameter and suitably connected, as at 12, to the stripper plate 8 by welding, brazing, or in any equivalent manner. A suitable coiled spring 13 encircles each stud 10 and the lower end thereof rests upon an internal shoulder 14 in each guide

stud 10, while the upper end of each spring 13 engages the lower face of the stripper plate 8. The lower end of each guide stud 10 is provided with a screw 10' which is provided with a head 15 adapted to engage the lower face of each die to limit upward movement of the stripper plate and to facilitate removing the stripper plate and the hereinafter mentioned associated parts from the die, or dies, as a unit, as is manifest.

To further secure the stripper plate 8 against lateral displacement upon the die, or dies 2, I, preferably, although not necessarily, employ guide pins 16 which are suitably secured to and depend from the stripper plate 8 and each of which is slidable in an opening 17 in the die, or dies 2.

A suitable safety kick member 18 is suitably secured to the underface of the stripper plate 8, preferably, at the rear edge thereof so as to be movable with the stripper plate. This safety kick member 18 is, as is manifest, employed to prevent the press from becoming operative until it comes into contact with a member of the press, not shown.

A suitable mask plate 19 is secured at one edge to one edge of the stripper plate 8 by means of suitable hinges 20 so that the mask plate 19 will also be a unit with the stripper plate 8 and the safety kick member 18 and move therewith, as is clearly shown in Fig. 2. The mask plate 19 is provided with a suitable sight opening 21 adapted to register with each of the die cutting edge receiving openings 9 in the stripper plate 8. The sight openings 21 in the mask plate 19 are relatively larger than the openings 9 in the stripper plate 8 so that the stitching 22, other marking, or the outline of the shoe part to be perforated, such as a shoe quarter 23, or other part of a lady's shoe surrounding any part 24 that is to be perforated, or cutout, can be readily observed by the operator when the shoe part is placed upon the stripper plate 8 under the hinged mask plate 19, as clearly shown in Fig. 1, of the drawing, which drawing shows the quarter of a shoe positioned over one of the dies to be perforated thereby.

It will be here observed, that the mask plate 19 being hingedly supported by the stripper plate 8 eliminates any possibility of the mask plate 19 being jarred or moved out of register with the stripper plate 8, as the two members act as a unit due to their hinged connection. This arrangement overcomes such difficulties as poor registering of the mask plate with the stripper plate as is now experienced when the mask plate is supported by any supporting member other than the stripper plate itself. When the mask plate 19 and the stripper plate 8 are arranged or connected as a unit, the material to be perforated lays flat on the stripper plate and at no time is it possible for the straps 25 on the shoe quarters to bend and interfere with

the speed of the operator as it is securely held between the stripper plate and the mask plate.

The many advantages of having the mask plate hingedly connected to the stripper plate and likewise of having the safety kick member applied to the stripper plate will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

1. In a stilt anvil cutout die for shoe cutouts, a die holder, a yieldably supported stripper plate therefor and a mask plate hingedly connected to the stripper plate.
2. In a stilt anvil cutout die for shoe cutouts, a die holder, a stripper plate yieldably supported by the die holder, a mask plate hingedly connected at one edge to the rear edge of the stripper plate to prevent shifting of the mask plate relative to the stripper plate and so the stripper plate and the mask plate will be movable upon the die holder as a unit.

In testimony whereof, I have hereunto affixed my signature.

CHRISTIAN A. CADENBACH.
